UNITED STATES PATENT OFFICE.

ARTHUR R. BARNETT, OF SEATTLE, WASHINGTON.

REFRIGERATOR.

1,232,268.

Specification of Letters Patent.

Patented July 3, 1917.

Application filed January 12, 1916. Serial No. 71,801.

To all whom it may concern:

Be it known that I, ARTHUR R. BARNETT, citizen of the United States, residing at Seattle, in the county of King and State of Washington, have invented a certain new and useful Improvement in Refrigerators, of which the following is a specification.

My invention relates to improvements in refrigerators, and the object of my invention is to provide a refrigerator which shall be adapted for household use and within whose interior space the temperature may be maintained at a much lower degree than the temperature of the external atmosphere without the employment of ice or artificial chemical agents, whereby articles of food, if disposed within said refrigerator, may be kept cooler than said external atmosphere.

I accomplish this object by devices illustrated in the accompanying drawings wherein Figure 1 is a view of a structure embodying my invention, in vertical section on broken line *x*, *x* of Fig. 3; Fig. 2 is a view of the same in vertical section on broken line *y*, *y* of Fig. 1; Fig. 3 is a view of the same in horizontal section on broken line *z*, *z* of Fig. 1; Fig. 4 is a view of another structure, embodying a modified form of parts of my invention, on broken line *a*, *a* of Fig. 6; Fig. 5 is a view of the same in vertical section on broken line *b*, *b* of Fig. 4; Fig. 6 is a view of the same in horizontal section on broken line *c*, *c* of Fig. 4; and Fig. 7 is a view in perspective of a detail of the same.

Referring to the drawings, throughout which like reference numerals indicate like parts, 8 designates an inclosing case whose interior space is divided into two chambers 9 and 10 by a vertical partition 11 that is so disposed to extend between the bottom wall 12 and the top wall 13 of said case 8 that the chamber 10 is almost four times as large as the chamber 9, said chamber 10 being adapted to serve as a receptacle for articles of food that are to be kept cool.

Within the larger chamber 10 is a conduit 14 for water, of rectangular cross-section, of such width as adapts it to extend throughout the distance between the vertical front wall 15 and the vertical back wall 16, and of such length as adapts it to extend from the lower end portion of the partition 11 to the upper end portion thereof in a staggered

course between said partition 11 and the vertical side wall 17, whereby are formed three horizontal shelves 18, 19 and 20, as shown more clearly in Fig. 1, upon which shelves food may be stored.

The under wall of that portion of the conduit 14 that forms the horizontal shelf 18 declines from the partition 11 to the vertical side wall 17 and the under wall of that portion of said conduit 14 that forms the horizontal shelf 19 inclines between said wall 17 and the partition 11, while the under wall of that portion of said conduit 14 that forms the shelf 20 inclines toward said wall 17, and the under wall of that portion of said conduit 14 which is adjacent to the horizontal top wall 13 inclines between the wall 17 and the top end portion of the partition 11, whereby water within said conduit 14, as it circulates to flow upwardly therethrough in response to the absorption of heat, shall always have an inclined path through said conduit 14 from that point that is adjacent to the bottom end portion of the vertical side wall 17 to that point of it that is adjacent to the top end portion of the partition 11.

The under wall of that portion of said conduit 14 that forms the shelf 18 is declined from the partition 11 in order that the whole of said conduit 14 and its associated parts may be wholly emptied and drained, as may be required, by turning the handle of a faucet 21 whose nipple is connected with said conduit 14 at a point adjacent to the bottom wall 12 to extend outwardly through the vertical side wall 17 as shown.

In the lower portion of the chamber 9 are a plurality of headers 22 whose nipples extend through the partition 11 to connect with the lower end of the conduit 14, while in the top portion of said chamber 9 is a like number of headers 23 whose nipples extend through the partition 11 to connect with the upper end of said conduit 14 in positions corresponding to the positions of the headers 22 in the bottom portion of the chamber 9.

Each of the headers 22 is provided with two upwardly projecting flanged sockets, as sockets 24, and each of the headers 23 is provided with two downwardly projecting flanged sockets 25, and disposed to extend vertically between each of corresponding ones of the sockets 22 and 23 is a conduit

of porous material, as conduits 26, all of said headers being provided with passageways through which water may flow between said vertically disposed porous conduits 26 5 and the conduit 14.

Extending downwardly from the chamber 9 through the bottom wall 12 are a plurality of air holes 27 and extending upwardly from said chamber 9 through the top wall 13 are 10 a plurality of other air holes 28, whereby air may enter the bottom of said chamber 9 to rise upwardly therethrough and flow outwardly from the top thereof or vice versa.

Upon the top wall 13 of the case 8, near 15 the back wall 16 thereof, is a funnel 29 which is provided with a removable cover 30, the nipple of which funnel 29 projects downwardly through the top wall 13 to connect with the conduit 14, through which 20 funnel 29 water may be poured in the operation of filling the conduit 14 and the associated porous conduits 26.

The vertical front wall 15, of the case 8, is provided with a door 31 which may be 25 opened to gain access to the interior to the larger chamber 10.

The conduit 14 and headers 22 and 23 may be made of sheet metal, as galvanized sheet iron, or they may be made of molded pottery as may be desired, and for some conditions of use they may be made of cast iron; but the vertically disposed conduits 26 must be made of porous material, as porous earthen ware, coarse vulcanized wood fiber, 35 paper fiber or the like, so that water may percolate through the walls thereof to moisten their exterior surfaces.

In Figs. 4, 5, 6 and 7, I have illustrated a modified form of internal parts of a refrigerator embodying my invention wherein 40 the larger chamber 32 (which corresponds to the larger chamber 10 of Figs. 1 and 3) is provided with a conduit made of an iron pipe 33 which is formed and disposed to extend from the lower portion of the smaller chamber 34 (which corresponds to the smaller chamber 9 of Figs. 1 and 3) through a partition 35, thence adjacent to the vertical wall 36 in a decline to a point adjacent 45 to the vertical side wall 37 where it connects with a T fitting 38, to one terminal of which is connected a draining faucet 39 (which corresponds to the faucet 21 of Figs. 1 and 3) from which T fitting 38 said pipe 33 extends on an incline to stagger back and forth and upwardly adjacent to the vertical side wall 37, the vertical back wall 36 and the vertical partition 35 to the top portion of the larger chamber 32 to a point adjacent 50 to the partition 35 there to connect with a T fitting 40, to one terminal of which is connected the nipple 41 which extends upwardly through the horizontal top wall 42 to connect with a funnel 43 (which corresponds 55 to the funnel 29 of Figs. 1 and 2), while the

remaining terminal of the T fitting 40 connects with a nipple 44 which extends through the partition 35 into the smaller chamber 34.

Within the chamber 34, at the bottom portion thereof, is a header 45 to which is connected the bottom end of the iron pipe 33, and which header 45 is provided with a plurality of upwardly projecting sockets 46, while in the top portion of said smaller chamber 34 is a header 47 to which is connected the nipple 44 and which is provided with downwardly projecting sockets 48 which correspond in number to the number of sockets in the header 45, and between each of corresponding ones of the sockets 46 and 48 is a vertically disposed conduit of porous material, as conduits 49 (which correspond in form and function to the porous conduits 26 in Figs. 1 and 3).

Within the larger chamber 32 are pairs of rods 50, 51 and 52 whose opposite ends project respectively into the partition 35 and vertical end wall 37 at different points in elevation, and upon each pair of said rods is removably disposed a tray 53 of the form shown in Fig. 7, whose walls are perforated to form air passageways and one of whose side walls is disposed to serve as a shelf 53, as more clearly shown in Fig. 5, upon which shelf 53 may be disposed articles of food.

Like the structure of Figs. 1, 2 and 3, the front wall 54 is provided with a door 55 by which one may gain access to the interior of the larger chamber 32.

The smaller chamber 34, like the chamber 9 of Figs. 1 and 3, is provided with air holes 56 extending through both its top and bottom walls whereby air may flow through said chamber 34.

The mode of operation of the refrigerator shown in Figs. 1, 2 and 3 and that of the refrigerator shown in Figs. 4, 5 and 6 is exactly the same and such operation may be described as follows:

The porous conduits in the smaller chamber and the non-porous conduit in the larger chamber are filled with water poured through the funnel on top of the structure, which water may then soak through the walls of the porous conduits in said smaller chamber to moisten the surfaces of said porous conduits whereupon the air that is free to circulate through said smaller chamber will cause the moisture on the surfaces of said porous conduits to evaporate, which process of evaporation, in accordance with well known laws, will cool said conduits and the water therein contained, which cooler water will fall to the bottom of said porous conduits to flow therefrom into the bottom end of the conduit within the larger chamber to flow upwardly to the top end of said porous conduits, (as it absorbs the heat within said larger chamber) again to pass downwardly through said porous conduit again

to part with the heat absorbed by it in the larger chamber, thus continuing to circulate downwardly in the porous conduits and upwardly in the non-porous conduit in an 5 obvious manner to keep the interior of the larger chamber cool.

Obviously, changes may be made in the forms, dimensions and arrangement of parts of my invention without departing from 10 the spirit thereof.

What I claim is:

1. A refrigerator of the class described which embodies an inclosing case whose interior space is divided by a vertical partition 15 to form a larger chamber and a smaller chamber and which is further provided with a door in its front wall which opens into said larger chamber; a non-porous conduit for water, of oblong cross-section, disposed 20 to extend from the bottom portion of said smaller chamber through said vertical partition into said larger chamber and across the floor of said larger chamber, thence upwardly to the top of said larger chamber in 25 a staggered course to form a plurality of shelves therein, thence through the top end portion of said partition into said smaller chamber; a conduit of porous material vertically disposed in said smaller chamber 30 with its upper end connected with the upper end of said non-porous conduit and with its lower end connected with the lower end of said non-porous conduit; a funnel disposed to connect with the upper portion of 35 said non-porous conduit through which wa-

ter may be poured to fill said non-porous conduit and its associated porous conduit; a faucet connected to the lower portion of said non-porous conduit in a position to adapt it to be operated to drain all the 40 water from said non-porous conduit and its associated porous conduit that may be contained therein; and passageways for air extending through both the bottom wall and the top wall of said smaller chamber. 45

2. A refrigerator of the class described comprising a casing having a vertical partition dividing the same into two chambers, a double-wall tortuous water passageway in one chamber, a porous water passageway 50 in the other chamber and means arranged at the upper and lower ends of the last named chamber forming communication between the water passageways of each chamber. 55

3. A refrigerator of the described class comprising a casing divided into two compartments, headers having vertically aligned sockets positioned in the upper and lower ends of the casing, porous tubes positioned 60 in the aligned sockets, and a non-porous water receptacle communicating with the headers.

In witness whereof, I hereunto subscribe my name this third day of January A. D., 65 1916.

ARTHUR R. BARNETT.
